UNITED STATES PATENT OFFICE.

JOHN W. GILBERT, OF NEW YORK, N. Y.

AUTOMATIC AIR-REGULATOR FOR ORGANS.

SPECIFICATION forming part of Letters Patent No. 364,243, dated June 7, 1887.

Application filed March 24, 1886. Serial No. 196,311. (No model.)

To all whom it may concern:

Be it known that I, JOHN W. GILBERT, a citizen of the United States, residing at New York city, in the county of New York, and in the State of New York, have invented certain new and useful Improvements in Automatic Attachments for Organs; and I do hereby declare that the following is a full, clear, and exact description thereof.

The object of my invention is to provide organs or other musical instruments with air under all the variable quantities required, and also to enable the organ itself to regulate that supply automatically, so that the air-reservoir is kept full under all conditions of the working or playing of the said organ. This I effect by means of the transmission motion from the engine to the blowing apparatus of the organ, by using a friction-clutch to connect the motor-shaft with the shaft that gives the motion to the blowing apparatus. I operate the said clutch by a connection with the moving board of the air-reservoir of the organ, so that any variation of speed can be given to the shaft of the blowing apparatus, or stopped entirely whenever it may be necessary to do so, and at the same time keep the engine constantly in motion, so as to operate the blowing apparatus immediately, it is required to do so, to refill or keep up the supply in the organ, so that after the motor or engine is set in motion no further attention is necessary.

In order to more fully describe my invention, I will refer to the accompanying drawings, forming a part of this specification.

Figure I is a plan view of an organ, showing how my automatic attachment is connected thereto. Fig. II is a sectional view taken on line *x x*, Fig. I, showing the position of the rocking bar and shaft. Fig. III is a sectional view on line *y y*, Fig. I. Fig. IV is an enlarged sectional view of the clutch used in connection with my invention.

Letter A represents the organ, which may be of any construction. B is the bellows or blowing apparatus of the same operated by the crank-shaft C, having on its outer end outside the organ the pulley D. This crank-shaft and pulley are operated by belt E, passing around pulley F, fastened onto shaft G.

This shaft G is connected to the shaft H of the gas-engine I by means of the automatic clutch J. An enlarged view of same can be seen in Fig. IV.

To the air reservoir or receiver O of the organ is attached the rope or cable m, which passes over pulleys *nn'* and down to within an inch of the rocking bar P. This end of the rope or cable is fastened to the weights g. This rocking or cross arm P is attached to the rocking shaft R, which is journaled onto standards r r. One end of this rocking arm is provided with weights s s.

The end u of the rocking shaft R has attached to it the stirrup or forked arm w, which surrounds the grooved sheave or pulley j of the clutch J.

When the air-reservoir O of the organ is empty, the weight g, attached to the cable m, will be drawn up from the rocking bar P. This allows the said bar to tilt downward by reason of the weights g. When the said rocking arm is thus tilted, the forked arm w of the rocking shaft R causes the clutch J to operate and allow the engine-shaft H (which has been in motion) to transmit its motion to shaft G. When this is done, motion is immediately communicated to the crank-shaft C, through the agency of the belt E, which sets in motion the bellows or blowing apparatus of the organ. Now, as the air is pumped into the air-receiver O the weighted end of the cable m will drop down upon the free end of the rocking bar P and counterbalance the weighted end of said bar and bring it in a level position. When this is done, the forked arm w of the shaft R is thrown outward and releases the clutch and disconnects shaft H from shaft G, thus depriving the last-mentioned shaft of its motive power without stopping the engine.

As soon as the shaft G is disconnected from shaft H it will stop, likewise the crank-shaft C and bellows B; but as the air is being used, by reason of the playing of the organ, the weighted end of the cable m will rise and release its hold on the free end of the rocking bar P and permit it to tilt again, as described before, and perform automatically the herein-before named function of operating the clutch and connecting and disconnecting the shafts G and H, for the purpose of supplying the organ

with air without the stopping or starting of the engine—during the entire playing or using of the said organ.

The clutch shown in Fig. IV is the one that will be used in connection with my invention; but, as it is already patented, no claim will be made thereon, and no description has been made thereof as to its internal construction.

I am aware that any well-known clutch that will perform the office of transmitting motion from a running shaft to a stationary one can be used in connection with my invention.

My invention is applicable to any organ used in churches or other places.

15 Having thus described my invention, I desire to claim—

1. The automatic air-supplier for organs, consisting of the bellows with shaft G, given a differential or variable motion through the 20 action of the clutch J, fastened on the shaft H of the engine and regulated in movement from the said bellows by the cable m, having weight g attached, and the rocking arm P, fastened on the shaft R, substantially as and for the purpose set forth.

2. In an automatic air-supplier for organs, the cable m, attached to air-reservoir O, and

provided with weights g, in combination with rocking arm P, substantially as set forth.

3. In an automatic air-supplier for organs, 30 the rocking arm P, with weights s, and attached to rocking shaft R, having forked arm w, in combination with the cable m, substantially as set forth.

4. In an automatic air-supplier for organs, 35 the forked arm w, attached to the shaft R, with the rocking arm P, in combination with the clutch J, substantially as described.

5. In an automatic air-supplier for organs, 40 the shaft G, with pulley F, in combination with the clutch J and shaft of engine H, substantially as set forth.

6. In an automatic air-supplier for organs, the crank-shaft C, with pulley D, in combination with belt E and shaft G, substantially as 45 set forth.

In testimony that I claim the foregoing I have hereunto set my hand this 11th day of February, 1886.

JOHN W. GILBERT.
